UNITED STATES PATENT OFFICE

2,154,990

FOUNTAIN BRUSH

Michael Ombrello, New York, N. Y.

Application October 8, 1938, Serial No. 234,034

1 Claim. (Cl. 15—122)

This invention relates to brushes and more particularly to fountain brushes.

An object of the invention is to provide a brush so constructed as to hold soap or the like in the head or body thereof, and having means whereby the soapsuds may be distributed over the body or surface to be cleaned during the scrubbing of said body or surface.

The brush constituting the subject matter of this application involves certain new and useful improvements over the type of brush forming the subject matter of an application for U. S. Letters Patent, Serial No. 202,089, filed by me under date of April 14, 1938, and entitled "Fountain brush."

The present invention, together with its objects and advantages will be best understood from a study of the following description taken in connection with the accompanying drawings wherein:

20 Figure 1 is a side elevational view of a brush embodying the features of the present invention.

Figure 2 is an end elevational view thereof.

Figure 3 is a top plan view of the brush.

Figure 4 is a top plan view of the brush with 25 the cover plate removed.

Figure 5 is a bottom plan view of the brush.

Figure 6 is a detail sectional view taken substantially on the line 6—6 of Figure 3.

Figure 7 is a fragmentary detail sectional view 30 through one end of the cover plate showing a retaining element therefor and associated therewith.

Figure 8 is a fragmentary detail sectional view 35 showing the manner of securing the bristles to the body or head of the brush.

Figure 9 is a perspective view of a weight member.

Figure 10 is an elevational view of a roller, and

Figure 11 is an end elevational view of the 40 roller.

Referring more in detail to the drawings it will be seen that in accordance with this invention the brush comprises a substantially rectangular, or body member 5 to one side 6 of which are secured in any conventional manner, such as 45 through the medium of staples or other fastening elements 7 bristles 8.

At the top side thereof, or the side opposite to the side 6 thereof, the head or body 5 is open, and for said open side there is provided a closure plate 9.

The body or head 5 is of hollow construction to provide a chamber 10 that accommodates a bar of soap 11.

55 The soap 11 is in contact with the periphery of

a roller 12 mounted on a shaft 13 suitably journaled within an opening 14 provided in the bristle equipped side 6 of the head or body as shown.

To maintain the soap 11, as it shifts back and forth within the chamber 10, in intimate contact with the periphery of the roller 12, there is provided a weight 15.

The weight 15 as shown is in the form of a rectangular rimmed plate of metal or other suitable material fitting conformably within a cover 16 of rubber or other suitable material provided therefor. The weight 15 accommodates within the confines of the rim or flange thereof the bar of soap 11 as shown in Figure 6 and serves, as it is obvious, to maintain the soap 11 in contact with the periphery of the roller 12.

Also to protect the opposite end walls of the chamber 10, and to deaden the sound incident to the shifting of the soap and the weight from one 20 end to the other of the head or body 5 said chamber 10 at said opposite ends thereof is lined with cushioning material 17 of rubber or other suitable sound-deadening material.

The bristles 8 adjacent the opening 14 accommodates the roller 12 so that the periphery of the roller is slightly inwardly from the scrubbing surface formed by the bristles 8 as shown in Figure 6. Obviously, in using the brush with the soap 11 within the chamber 10 contact of the 30 soap with the periphery of the roller 12 will result in the formation of suds which will be carried by the roller to the surface of the bristles 8 for application to the body being scrubbed.

From the above it will be appreciated that with 35 this invention the soap is substantially automatically applied to the bristles of the brush to the end that application of soap to the brush is obtained without thought or attention on the part of the user. Thus the necessity of employing one hand 40 for holding the brush and the other hand for holding the soap for the purpose of "soaping" the brush is dispensed with.

The invention as above described is substantially identical with the invention as described 45 in my aforementioned and identified co-pending application.

However, in accordance with the present invention means is provided for positively maintaining the cake of soap 11 in constant contact 50 with the periphery of the roller 12 when such as desired. Such means, in the preferred embodiment thereof, is in the form of a spring 18 that at one end is anchored to the underside of the cover plate 9 as at 19. The free end of the spring 55

18 bears, as clearly shown in Figure 6, against the covered side or exterior of the weight 15 and thus exerts a pressure on the weight and the soap bar 11 associated therewith for maintaining the soap 5 bar 11 in constant intimate contact with the periphery of the roller 12.

Further in accordance with the present invention the cover plate 9 is provided with a finger-accommodating opening 20 through which a finger 10 may be inserted into the chamber 10 and engaged with the spring 18 for flexing the spring out of contact with the weight 15 thus leaving the soap bar 11 and weight 15 free to shift within the confines of the chamber 10 as may be desired.

15 Further in accordance with the present invention, instead of having the cover plate 9 in the form of a slide closure as is the case with the brush forming the subject matter of my herein-before identified co-pending application, said 20 closure plate 9 is releasably held in engagement with the head or body 5 of the brush through the medium of split expansible studs 21 that have threaded shanks 22 screwed into the cover plate 9 at opposite ends of the latter.

25 Further, the head or body member 5 has the opposite end walls thereof provided with sockets 23 as best shown in Figure 6, to accommodate the expansible studs 21. Obviously, to secure the closure 9 at the open side of the head or body 5 30 studs 21 are forced into the sockets 23 and expand within the sockets to frictionally engage the walls thereof and thereby maintain the cover plate 9 in a positive and efficient manner on the head 5 for closing the open side of said head.

35 From the above it will also be apparent that in actual practice springs 18 will serve effectively for holding the soap 11 against the periphery of the roller 12 when the brush is held in a vertical or perpendicular position. Thus with this invention the soap is held in constant contact with the 40 periphery of the roller 12 regardless of the posi-

tion of the brush thereby insuring a constant transfer of the soap from the bar thereof to the bristles 8.

It is thought that a clear understanding of the construction utility and advantages of a fountain brush embodying the features of the present invention will be had without a more detailed description.

Having thus described the invention what is claimed as new is:

A brush of the class described comprising an open-top box-like head forming a rectangular chamber for containing a bar of soap, said chamber being larger than the bar of soap to permit movement of said bar therein from side to side 15 thereof, and the bottom of the head having a central aperture therein for the discharge of soap-suds therethrough, bristles extending from the bottom of said head, a roller journaled in the bottom of the head, said roller extending into 20 the chamber and supporting said bar in elevated position off said bottom, said roller depending below said bottom for engagement with the floor whereby under movement of the head back and forth said roller is caused to rotate and tend to 25 frictionally drive said bar from side to side of said chamber, a flanged cap-like weight member fitting over said bar and forcing the same into intimate contact with said roller, a cover detachably secured to said head, and a leaf spring attached at one end to the under face of the cover at one side thereof and having a free end bearing on said weight to hold the weight and bar stationary against movement back and forth, said cover being provided with an aperture therein 30 over said free end of the spring for access to said end to raise the same off said weight and release said weight and bar at will for movement back and forth.

MICHAEL OMBRELLO.
